UNITED STATES PATENT OFFICE.

GEORGE S. SHAW, OF SPRINGFIELD, OHIO.

GAS-ENGINE.

SPECIFICATION forming part of Letters Patent No. 641,156, dated January 9, 1900.

Application filed June 5, 1899. Serial No. 719,364. (No model.)

To all whom it may concern:

Be it known that I, GEORGE S. SHAW, a citizen of the United States, residing at Springfield, in the county of Clark and State of Ohio, 5 have invented certain new and useful Improvements in Gas-Engines, of which the following is a specification, reference being had therein to the accompanying drawings.

This invention relates to certain new and 10 useful improvements in gas-engines.

The particular features of my invention have reference to governor-controlled mechanism for regulating the transmission of the sucking force of the piston within the cylinder to an air and gas or gasolene inlet valve-operating device, whereby when the engine exceeds a maximum speed the inlet-valve will 15 close the air-inlet passage more or less, while at the same time the proper ratio of gas, &c., 20 and air will be maintained.

My invention also relates to details of construction and arrangement hereinafter appearing, and particularly pointed out in the claims.

25 In the accompanying drawings, on which like reference letters and figures indicate corresponding parts, Figure 1 represents a partial side elevation of a gas-engine with my improvements applied thereto; Fig. 2, a partial 30 end elevation of the same, showing my improvements applied thereto; Fig. 3, a sectional view on the line *x x* of Fig. 1 looking in the direction of the arrows, and Fig. 4 a sectional view on the line *y y* of Fig. 2 also looking in 35 the direction of the arrows.

In gas-engines it has usually been the custom to cut off the supply of gas or gasolene, &c., when the engine was running fast without affecting the air-supply. This arrangement was detrimental to the explosive mixture, and consequently when the engine required another charge the charge was not up to the proper standard, with the result that the engine would run down to a low speed. 40 Such fluctuation of the speed was very detrimental to the proper working of the engine, and in some cases wholly unfitted it for use at all. With my construction, however, the quality of the mixture always remains the 45 same, while the quantity is regulated according to the speed or load of the engine.

The letter A represents an engine-cylinder,

to one side of which extends a projection B. This projection B has a screw-threaded opening C, into which is screwed a nipple D. 55 Upon this nipple is screwed my governor attachment E. Such attachment is bored out, as shown at F, and has mounted therein a rotatable or partially-rotatable cut-off valve G, within which is what I term a "mixing-chest" 60 H. This cut-off valve is supplied with suitable openings I, J, and K, respectively, the opening I communicating with the inlet-passage L, leading into the engine-cylinder, while the passage J connects with the gas or gaso- 65 line supply pipe and the passages K with the air-supply pipe, such pipes being illustrated at M and O, respectively. The cylinder-valve is provided with gudgeons P and Q, respectively, the former of which has a bearing in a cap R, while the latter of which extends through the opposite end S of the cylinder-casing and has mounted on its outer end a crank T in any suitable manner. This crank 70 is slotted, as shown at U, to receive a pin or 75 stud V, projecting from a piston-stem W, such stud being held in place in the slotted crank by a nut X. At right angles to the cylinder G and slightly elevated above it is mounted a cylinder Y, which I will term the "suction-cylinder," 80 for the reason that it is operated by the suction from the engine-cylinder, as will hereinafter appear. Within this cylinder is mounted a piston Z, to which is connected a piston-stem W, above referred to. As this 85 piston-stem is moved up and down the pin V will act to rock the crank T, and the slot U in the crank will permit such rocking without deflecting the stem W, so that there is no binding of the stem in the bearings in the cylinder ends. It will be observed that I have provided a passage 2, which I term a "suction-passage," connecting with the inlet-passage L and extending above the same and connecting with the lower end of the suction-cylinder Y, 90 as clearly seen in Fig. 4. In the passage 2 is mounted a valve 3, which has stems 4 and 5 extending in opposite directions therefrom. The stem 4 passes through a stuffing-box 6 and is adapted to be operated upon by a lever 100 7, pivoted to an extension 8 from the frame structure E. The stem 5 projects within a recess 9 and is adapted to be pressed upon by a spring 10, the latter of which holds the valve

3 upon its seat when not acted upon in a manner presently to appear. Thus the stem 4 normally holds the lower end of the lever in its outermost position.

5 I will now refer to the governor mechanism and the manner in which the piston in the suction-cylinder is operated. The attachment E carries a sleeved bearing 11, which is adapted to receive a hollow shaft 12 therein, 10 such shaft being held from pulling out of the sleeve by means of a collar 13, secured thereto by a set-screw 14, and a pulley 18, cast or otherwise secured thereto, such collar and pulley being at the respective ends of said sleeve. A 15 pair of governor-balls 16 are pivoted to said hollow shaft near its outer end, as shown at 17. Arms 22 in the nature of bell-crank levers extend from said balls and project within notches or recesses 23 in a shaft 15 and act to 20 reciprocate said shaft in one direction to rock the lever 7 to the dotted-line position, as shown in Fig. 3. A tension-spring 21, mounted upon the shaft 15 between a knurled nut 20 and a washer 21', acts to return said shaft to its outward position when the governor-balls are in 25 their normal position. The knurled nut may also be secured more or less on the shaft 15 to regulate the tension of the spring 21, according to the desired speed of the engine, in 30 a manner well known, it being understood that the governor-balls are operated through the pulley 18 by means of a belt or other suitable means. The inner end of the shaft 15 carries a spring-bumper 24, which is adapted 35 to yield when coming in contact with the lever 7, so as to prevent noise, as might possibly be the case where the shaft 15 itself came in direct contact with the lever.

Let us suppose that the governor-balls are 40 placed under the proper tension to remain in their normal in position when the engine is running, say, at a speed of one hundred and fifty revolutions per minute and that such speed is being exceeded. This will immediately cause the governor-balls to fly outward, 45 which action will shift the shaft longitudinally in its bearings and will throw the upper arm of the lever 7 inward, while its lower arm is thrown outward, as shown in dotted lines in 50 Fig. 3. This action of the lever will cause the valve 3 to be raised from its seat, which will open the passage 2, and consequently the sucking action of the piston in the engine A (not shown) will continue to create more or 55 less of a vacuum in such passage, and as this passage is connected with the suction-cylinder a partial vacuum will be formed beneath its piston, which will instantly cause it to descend; but as soon as this occurs the piston-stem, which engages with the crank T, 60 rigidly mounted upon the gudgeon Q, projecting from the inlet-valve, partially rotates such inlet-valve, which more or less closes the gas and air inlet passages simultaneously, thereby 65 diminishing the mixture passing into the engine-cylinder. The instant, however, the speed of the engine returns to normal the

valve 3 is seated and a spring 25 again returns the piston Z to its normally-raised position, a spring 26 within the cap 27 of the cylinder 70 Y acting to cushion the upward stroke of the piston, so that there is no pounding or noise due to the piston suddenly assuming its normal position. It will be understood, of course, that this spring is much weaker than the 75 spring 25. This upward movement of the piston Z in the suction-cylinder will again partially rotate the inlet-valve, so as to again fully open the air and gas or gasoline ports, thereby permitting a normal charge to again enter 80 the engine-cylinder.

Thus with my improvements I am enabled to quickly regulate the speed of the engine without diminishing the quality of the charge mixture employed, while at the same time the 85 quantity of the charge mixture may be quickly regulated in accordance with the speed of the engine, particularly when running above a predetermined or normal speed.

In order to prevent the explosive charge 90 from passing back through the inlet-passage on the compression-stroke of the engine-piston, a valve 28 is provided of the ordinary or any approved construction.

Having thus fully described my invention, 95 what I claim as new, and desire to secure by Letters Patent, is—

1. In a gas-engine, the combination with an engine-cylinder having an inlet-passage and a suction-passage communicating therewith, 100 a governor attachment connected with said inlet-passage, said attachment having a mixing-chamber therein, an inlet-valve mounted within said mixing-chamber, air and gas pipes communicating with said mixing-chamber 105 and adapted to be more or less cut off by said valve, a suction-cylinder carried by said attachment and connected with said suction-passage, a piston mounted in said cylinder carrying a piston-stem, means for connecting 110 said stem with said inlet-valve, a governor-controlled valve in said suction-passage for regulating the sucking action of the engine-piston upon the suction-piston, whereby said suction-piston will be operated in one direction to more or less rotate said inlet-valve, and means to return said suction-piston to 115 normal position, thereby rotating said inlet-valve to its normal position, all substantially as shown and described. 120

2. In a gas-engine, the combination with an engine-cylinder having an inlet-port communicating therewith, of a governor attachment having an inlet-passage and a suction-passage therein, both of which communicate 125 with said engine inlet-passage, an inlet-valve mounted in said attachment inlet-passage and adapted to more or less cut off the supply of air and gas, a valve adapted to normally close said suction-passage, a centrifugal governor adapted to operate said second valve to open it, a suction-cylinder communicating with said suction-passage, a piston mounted therein having a stem, a crank con- 130

nected with said inlet-valve and with said stem, a spring to operate said suction-piston in the opposite direction to that caused by the suction, all substantially as shown and described.

3. In a gas-engine, the combination with an engine proper having an inlet-passage communicating therewith, of a governor attachment connected with said inlet-passage and having a continuation of said inlet-passage, and a suction-passage communicating therewith, an inlet-valve having air-inlet, gas and explosive-mixture ports therein, a suction-cylinder, a suction-piston mounted therein having a stem extending therefrom, a crank connected with said inlet-valve having a slotted opening therein, a stud projecting from said piston-stem and adapted to project within said slot, a valve in said suction-pas-

sage having a stem extending therefrom, a pivoted lever carried by said attachment, one of whose arms is adapted to engage with said valve-stem, a slidably-mounted shaft arranged to engage with the other arm of said lever, a governor device for operating said shaft and a spring to normally hold said valve seated, whereby the inlet-valve is operated to cut off more or less of the supply of air and gas when the speed of the engine is above the normal, and means for setting the governors for such normal speed, all substantially as shown and described.

In testimony whereof I affix my signature in presence of two witnesses.

GEORGE S. SHAW.
